FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 563,068 S
APPLICATION NO. : 29/266598
DATED : February 26, 2008
INVENTOR(S) : Weilai Jiang

Page 1 of 1

It is certified that error appears in the above-identified patent and that said Letters Patent is hereby corrected as shown below:

*On Title Page

Item [57] Claim – Below “described” insert -- This application incorporates by reference the Chinese Design Application No. 300140004.1, filed March 31, 2006. All the material from said Chinese Design Application, which is essential to the claimed design, is included in this application. It is understood that any material in said Chinese application, which is not present in this application, forms no part of the claimed design. --.

Signed and Sealed this

Third Day of June, 2008

JON W. DUDAS
Director of the United States Patent and Trademark Office
